UNITED STATES PATENT OFFICE.

LOUIS IVES, OF DEARBORN, MICHIGAN.

AUTOMATIC DOOR OPENING AND CLOSING DEVICE.

1,246,101.

Specification of Letters Patent. Patented Nov. 13, 1917.

Application filed December 27, 1916. Serial No. 139,195.

To all whom it may concern:

Be it known that I, Louis Ives, a citizen of the United States of America, residing at Dearborn, in the county of Wayne and State 5 of Michigan, have invented certain new and useful Improvements in Automatic Door Opening and Closing Devices, of which the following is a specification, reference being had therein to the accompanying drawings.

10 The invention relates to an automatic door opening and closing device in which a horizontally swinging door is automatically opened and closed by means of a substantially vertically movable platform. The object of my invention is to obtain a construction in which the connections between the platform and door will operate smoothly and efficiently and at the same time are simple in construction, neat in appearance, 20 and may be easily assembled. It is another object of the invention to obtain a construction in which there is no open space between the platform and the flooring, within which the platform is located, at any time in the 25 movement of the platform; and further to obtain various advantages hereinafter set forth.

In the drawings:

Figure 1 is a sectional view of the construction embodying my invention;

Fig. 2 is an enlarged perspective view of the connections between the door and the platform;

Fig. 3 is a fragmentary longitudinal view 35 thereof;

Fig. 4 is a cross section upon the line 4—4 of Fig. 3; and

Fig. 5 is a detail view.

A represents the platform located within 40 the recess B' in the flooring B and mounted upon the supports A' pivotally mounted upon the arms A² fixedly secured to the rock shafts A³ extending across and rotatably mounted in the frame A⁴. For the purpose 45 of maintaining the platform in its normal, or upper position, the members C are fixedly secured to the rock shafts A³ and connected by the member C' which is engaged at one end by the spring C² secured to the frame 50 A⁴. In order to provide a simple and easily assembled connection which will properly operate, the member D is fixedly secured to the rock shaft A³ and extends outwardly and upwardly therefrom, its outer end having 55 a recess D' therein adapted to be engaged by the reduced end of the sleeve E. The

platform A is provided with the aperture Q for permitting the sleeve E to extend therethrough. Rotatably fitting within the sleeve E is the pin F to the outer end of 60 which is pivotally secured the member G, to which in turn is rotatably secured the member G' by means of the shouldered pin H extending axially therethrough and into the member G and secured to the latter by means 65 of the transverse pin G². The member G' is rotatably secured to the pivot member I pivotally mounted in the bracket I' secured to the horizontally swinging door J.

For the purpose of adjusting the amount 70 of swing of the door J, the collar K upon the sleeve E is provided with the set screw K' passing therethrough and adapted to engage the sleeve, and the pin F is provided with the transversely extending pin F', 75 adapted to engage the internal annular groove K² of the collar through the diametrically opposite openings F² in one side of the annular groove, the sleeve E being cut away at the diametrically opposite sides 80 E' sufficiently to permit of relative rotative movement of the pin F and the collar K. As is readily apparent the amount of swing 85 of the door J can be increased by an upward adjustment of the collar K upon the sleeve E, or decreased by a downward adjustment thereof.

In operation downward movement of the platform A actuates the rock shafts A³ which rock the member D, the sleeve E and the 90 pin F which in turn moves the members G and G' longitudinally and also relatively horizontally to swing the door J. During this operation the pivot member I rotates horizontally in the bracket I', the member 95 G' rotates vertically relative to the pivot member I and also rotates relatively to the member G about the longitudinal axis passing through the members, the member G rotates vertically relative to the pin F, and the pin F rotates horizontally relative to the sleeve E and the collar K. This construction is such that the door J will open or close easily and smoothly without any binding or unsteady movement taking place. 100 105

As shown in the drawings, the member D is located within the frame A⁴ and the support A' is pivotally secured thereto, as at D², the arm A² not being necessary. It is also understood that the member D can be 110 secured to the rock shaft A³ outside of the frame A⁴ and with the other connections

pass upwardly through the leaves L, the arm A² within the frame being necessary under these conditions.

Another feature of the invention relates to 5 the means for avoiding the open space which would occur between the platform A and the flooring B upon relative movement thereof, this means comprising the leaves L resting upon the platform and flooring and 10 permitting of relative movement thereof. In the present instance the leaves L are pivotally secured to the platform A by means of the pins M loosely fitting within the apertures M' in the leaves, the leaves sliding 15 ably engaging the flooring B. For the purpose of having a practically level surface and at the same time a weather-proof construction the platform A is provided with the thin flat member N, preferably formed 20 of metal, extending around its periphery and mounted upon the member O, to be spaced a sufficient distance above the leaves L to permit of the necessary rocking movement thereof. Within the recess inclosed 25 by the members N and O a suitable insert P of rubber or other material is located, the top of this insert being substantially flush with the top of the member N.

From the above description it can be 30 readily seen that my construction is simple and compact, may be readily assembled and moreover efficiently performs its functions. Furthermore the construction is such that it has a neat and pleasing appearance.

35 What I claim as my invention is:

1. In an automatic door opening and closing device, the combination with a door, of a platform, a rock arm actuated by said platform, a sleeve connected to said rock 40 arm, a pin rotatably mounted in said sleeve, a bracket upon said door, a pivot pin rotatably mounted in said bracket, and relatively rotatable members one of which is pivotally secured to said pin and the other 45 of which is pivotally secured to said pivot pin.

2. In an automatic door opening and closing device, the combination with a horizontally swinging door, of a substantially 50 vertically movable platform, a rock shaft operated by said platform, an outwardly and upwardly extending member fixedly secured to said rock shaft, a sleeve engaging said member, a pin rotatably mounted in 55 said sleeve, a bracket upon said door, a pivot pin mounted in said bracket, relatively rotatable members pivotally secured to said pin and pivot pin, and means for adjusting said pin longitudinally of said sleeve.

60 3. In an automatic door opening and closing device, the combination with a horizontally swinging door, of a substantially vertically movable platform, a rock shaft operated by said platform, an outwardly 65 and upwardly extending member fixedly se-

cured to said rock shaft, a sleeve engaging said member, a pin rotatably mounted in said sleeve, a bracket secured to said door, a pivot pin rotatably mounted in said bracket, relatively rotatable members pivotally secured to said pin and pivot pin, a collar adjustably secured upon said sleeve and provided with an internal groove and a transversely extending pin in said pin 70 engaging said groove, said sleeve being diametrically oppositely apertured to permit of said engagement and of relative movement of said pin and collar. 75

4. In an automatic door opening and closing device, the combination with a door, 80 of a platform, a rock arm actuated by said platform, a sleeve connected to said rock arm, a pin rotatably mounted in said sleeve, means for adjusting said pin relative to said sleeve, and connections between said pin and 85 said door.

5. In an automatic door opening and closing device, the combination with a flooring provided with a recess and a platform mounted in said recess and relatively movable to said flooring, of a member extending around the periphery of said platform, a flat member upon said member and projecting outwardly beyond the outer faces of 90 said member to provide a space between said flat member and said platform, and leaves extending from said flooring to said platform and engaging said space. 95

6. In an automatic door opening and closing device, the combination with a flooring 100 provided with a recess and a platform mounted in said recess and relatively movable to said flooring, of a member extending around the periphery of said platform and spaced above said platform, an insert located within the recess formed by said member and flush therewith, and leaves extending between said flooring and said platform and extending into the space between said member and platform. 105

7. In a device for operating a door from a platform, the combination of a rock arm actuated by said platform, a member secured to said rock arm, a second member extending in the same direction as said first-mentioned member and rotatably and longitudinally adjustably engaging the same, and connections between said second member and the door. 110

8. In a device for operating a door from 115 a platform, the combination of a rock arm actuated by said platform, a sleeve secured to said rock arm, a pin rotatably mounted in said sleeve, a collar adjustably secured upon said sleeve and provided with a 120 groove, a transversely-extending pin engaging said first-mentioned pin and the groove in said collar, said sleeve being apertured to permit of said transversely-extending pin passing therethrough and of relative move- 125 130

ment of said first-mentioned pin and collar, and connections between said first-mentioned pin and the door.

9. In a device for operating a door from a platform, the combination with a member adapted to be actuated by the platform and a second member extending in the same direction as said first-mentioned member and rotatively engaging the same, of relatively rotatable members pivotally engaging said second member and the door.

10. In a device for operating a door from a platform, the combination with a member adapted to be actuated by the platform and a second member rotatively engaging said first-mentioned member, of relatively rotatable members pivotally engaging said second member and the door, and a pin extending axially into said last-mentioned relatively rotatable members at their adjacent ends, fixedly engaging the one and rotatably engaging the other of said members.

11. The combination with flooring and a platform relatively movable thereto, of leaves surrounding said platform and

mounted on the same and said flooring, and means for protecting and weatherproofing the portions of the leaves engaging said platform.

30

12. The combination with flooring and a platform relatively movable thereto, of a leaf pivotally secured to said platform and slidably engaging said flooring, and weatherproofing means for the pivotally secured portion of the leaf.

35

13. The combination with flooring and a platform relatively movable thereto, of a leaf pivotally secured to one of said elements and slidably engaging the other, and weatherproofing means for the portion of the leaf upon the platform element.

40

14. In a device for operating a door from a platform, the combination with a member adapted to be actuated by the platform, and a second member concentric with and rotatively engaging said first-mentioned member, connections between said second member and the door.

45

In testimony whereof I affix my signature. 50
